UNITED STATES PATENT OFFICE.

WILLIAM I. DERRICK, OF DAVENPORT, IOWA, ASSIGNOR TO WESTCO-CHIPPEWA PUMP COMPANY, OF DAVENPORT, IOWA, A CORPORATION OF DELAWARE.

PUMP.

Application filed August 18, 1927. Serial No. 213,813.

This invention relates to rotary pumps of the type disclosed in the Wahle Reissue Patent No. 16,074, granted on May 19, 1925, in which there is a rotor provided adjacent its periphery with impeller blades and in which a passage is provided along side the impeller blades through which water may have an unimpeded flow from the pump inlet to the pump outlet, means being provided for preventing back flow from the outlet to the inlet so that the water is caused to flow through the passage by the impelling action of the vanes, causing suction at the inlet and building up a pressure at the outlet.

An object of the present invention is to provide a rotary pump of the character above referred to in which the impelling vanes are disposed inwardly of the periphery of the rotor and in which lateral thrust on the rotor is avoided.

A further object is to provide a pump in which the unobstructed water passage from the inlet to the outlet is entirely within the rotor.

With the above and other objects in view, the invention may be said to comprise the rotary pump as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification in which:

Figure 1 is a sectional elevation of the pump with a portion of the pump to the right of the center plane of the rotor shown in section on the line indicated at 1—1 in Fig. 2.

Fig. 2 is a side elevation of the pump with a portion of the casing broken away to show the rotor.

Fig. 3 is a sectional view taken on the line indicated at 3—3 in Fig. 2.

Fig. 4 is a sectional view taken on the line indicated at 4—4 in Fig. 2.

Fig. 5 is an axial section showing a modified form of the invention.

Fig. 6 is an axial section showing a further modification of the invention.

Fig. 7 is a fragmentary side elevation of the rotor shown in Fig. 6.

Referring to the accompanying drawings, 55 the pump casing is shown formed in two sections indicated by the reference numerals 1 and 2, the casing sections being provided with peripheral flanges 3 which are secured together by bolts 4.

Section 1 of the casing has formed integrally therewith a base 5 which is adapted to be secured to a suitable support and the base 5 carries a bearing member 6. The opposite section of the casing is formed with 65 an integral bracket 7, which carries a bearing member 8 in axial alignment with the bearing member 6. A shaft 9 is journaled in the bearing members 6 and 8 and extends centrally through the casing, the casing 70 members being provided with glands 10 to prevent leakage of water around the shaft. A rotor 11 is fixed to the shaft 9 within the casing and this rotor is preferably in the

form of a disc having a continuous peripheral portion 12 and a continuous inner portion 13, the peripheral portion 12 and the inner portion 13 being joined by a central web 14 and integral vanes 15. Each of the vanes 15 is provided with a notch 16 extending inwardly from its outer edge and terminating short of the web 14, the notches 16 being of a width slightly less than the length of the vanes 15. The notches 16 in the vanes 15 are so disposed as to provide continuous unobstructed annular channels in each face of the rotor 11. The casing is provided with a peripheral inlet 17 and a peripheral outlet 18, the inlet 17 being connected with the annular channels upon opposite faces of the disc by passages 19, and the outlet 18 is connected to the channels by means of passages 20. The opposite internal faces of the casing are substantially flat and lie in close proximity to the continuous peripheral and inner portions 12 and 13 of the disc so as to prevent any substantial leakage of water to the periphery and center of the casing. Water

entering through the opposite inlet passages 19 is carried along by the vanes, and the unobstructed channel formed by the notches 16 of the vanes permits a continuous flow of water from the inlet to the outlet.

To cause the water to flow from the channels in the rotor into the outlet passages 20, the opposite walls of the casing are provided with internal projections 21 which have a close fit in the notches 16 formed in the

vanes so that they obstruct the annular channels between the inlet and outlet.

The projections 21 extend circumferentially a distance sufficient to cover a plurality of adjacent vanes so that an effective seal is provided between the inlet and outlet which prevents the water under pressure at the outlet from flowing to the inlet.

In Fig. 5 of the drawing there is shown 10 a modification of the invention in which the rotor 22 is provided with a single annular channel 23 in one face thereof, impeller vanes 24 being provided at the bottom of the channel. Casing 25 has a close fit upon the 15 rotor as in the modification first described. The inlet and outlet are arranged in substantially the same manner and the flow from the outlet to the inlet is obstructed by a portion of the casing extending into 20 the channel 23 as in the modification first described.

A further modification of the invention is shown in Figs. 6 and 7 of the drawing in which the rotor 26 is provided with a continuous peripheral portion 27 and a continuous inner portion 28 which are connected by integral vanes 29 which are disposed centrally of the rotor. The vanes 29 are of a width considerably less than the thickness of the rotor so that an unobstructed annular channel is provided on each side of the vanes. Casing 30 closely overlies the rotor as in the modifications previously described, but in view of the fact that the channels on opposite sides of the rotor are in communication through the spaces between the vanes it is not necessary to provide inlet and outlet passages to both sides of the rotor.

As in the modification first described, the 40 flow of water between the inlet and outlet is obstructed by projections on the wall of the casing extending into the channels, the water in this case being forced out through a single outlet at the side of the casing.

In each of the modifications above described, an unobstructed channel for flow of water from the inlet to the outlet is provided in the rotor itself, and the casing is formed to obstruct this channel between the inlet and outlet so that there can be no substantial leakage of water from the outlet back to the inlet and the water is impelled in a continuous stream from the inlet to the outlet. The wall of the casing forms one side only of the channel so that a comparatively small stationary surface area is in contact with the moving stream of water and consequently there is little frictional resistance to the flow of water through the channel.

In the modification shown in Figs. 1 to 4, lateral thrust on the rotor is balanced by providing identical channels and impelling vanes upon opposite sides of the rotor and in the modification shown in Fig. 6 lateral

thrust on the rotor is avoided by providing transverse apertures through the rotor between the impelling vanes.

It will be apparent, therefore, that the present invention, by employing a construction in which the channel for the water is in the rotor, provides a rotary pump of simple and compact design in which the frictional resistance to the passage of water through the pump from the inlet to the outlet is materially reduced, and that by preventing unbalanced lateral pressure on the rotor there is little tendency for the rotor to get out of true and the frictional resistance to turning movement of the rotor is reduced.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

What I claim is:

1. A rotary pump comprising a rotor having a continuous annular channel therein and impeller vanes alongside the channel, and a casing having portions closely overlying the rotor on opposite sides of the channel, and having an inlet and an outlet communicating with said channel, said casing having an inwardly projecting portion obstructing said channel between the inlet and the outlet to prevent return flow from the outlet to the inlet.

2. A rotary pump comprising a rotor in the form of a disc having a continuous annular channel in a face thereof and impeller vanes alongside the channel, and a casing having a side thereof closely overlying the face of the disc on opposite sides of the channel and having an inlet and an outlet communicating with the channel, said casing having a portion obstructing said channel between the inlet and outlet.

3. A rotary pump comprising a rotor having an annular fluid conducting channel, inwardly from its periphery and concentric therewith, said channel being open at one side of the rotor and having vanes extending across the same and inset with respect to the side face of the rotor, and a casing which has a wall closely overlying the side face of the rotor inwardly and outwardly of the channel and provided with an inlet and an outlet both communicating with said channel, said casing having a partition member between the outlet and inlet extending into said channel and closely overlying said vanes.

4. A rotary pump comprising a rotor having an annular fluid conducting channel, inwardly from its periphery and concentric therewith, said channel being open at one

side of the rotor and having vanes extending across the same and inset with respect to the side face of the rotor, and a casing which has a wall closely overlying the side face of the rotor inwardly and outwardly of the channel and provided with an inlet and an outlet both communicating with said channel, the side wall of the casing having an integral internal projection intermediate the outlet and inlet fitting in the channel and closely overlying said vanes, said projection extending circumferentially a sufficient distance to overlie a plurality of vanes.

5. A rotary pump comprising a rotor in the form of a substantially flat disc having annular channels upon opposite sides thereof, and a casing having substantially flat sides closely overlying opposite faces of said disc and inlets and outlets in said sides communicating with the channels of the

disc, said casing having partition members projecting into the channels between the outlets and inlets.

6. A rotary pump comprising a rotor in the form of a disc having a continuous peripheral portion and a continuous inner portion, integral vanes connecting said inner and peripheral portions, said rotor having a continuous annular channel formed by notches in said vanes, and a casing having a wall closely overlying the inner and peripheral portions of said disc and provided with an inlet and an outlet communicating with said channel, said casing having an internal projection between the inlet and outlet obstructing said channel.

In testimony whereof I affix my signature.

WILLIAM I. DERRICK.
